BEST AVAILABLE COPY

H. W. Corbett,

Permutation Lock.

Nº 222.

AI Patented Mar. 1, 1859.

18.528 - 29.528

Fig 1

Fig 2. | Fig 3.

Witnesses.

Martin Briggs
Ho Saunter

Inventor

Henry H. Crook

No. 223, to original Letters Patent No. 18,228.—Improvement in Locks.—I claim the combination of the disk D and centre V, toothed or corrugated, substantially as represented, for the purpose of fastening them securely together, but I do not confine myself to any particular size or shape or number of teeth, nor to any particular position on the disk or centre. HENRY W. COVERT.